UNITED STATES PATENT OFFICE.

ROCKWELL A. LOOMIS, OF RETALHULEU, GUATEMALA.

CARRIAGE SHIFT FOR TYPEWRITERS.

1,413,342.

Specification of Letters Patent. Patented Apr. 18, 1922.

Application filed April 8, 1921. Serial No. 459,652.

To all whom it may concern:

Be it known that I, ROCKWELL A. LOOMIS, a citizen of the United States, residing at Retalhuleu, in the Republic of Guatemala,

5 Central America, have invented certain new and useful Improvements in Carriage Shifts for Typewriters, of which the following is a specification, reference being had therein to the accompanying drawings.

10 This invention relates to carriage shifts for typewriters and has for an object to provide means for utilizing some member of the body for shifting the carriage of a typewriter, not normally provided for in the 15 make of the typewriter, as ordinarily manufactured.

It is well known that the present day typewriter provides for the writing of capital and lower case characters by the shifting 20 of the platen, or carriage, relative to the point of printing, or reversely, the shifting of the battery of type bars relative to the carriage. The shifting is ordinarily accomplished by keys similar to the printing keys 25 located in the bank of keys, by depressing which the shifting of the carriage or the battery of type bars is accomplished. The depressing of this shift key is ordinarily accomplished by the finger of the operator, 30 whereby the speed of operating is decreased, employing as it does a finger action which might otherwise be employed on a printing key.

The present invention provides for the 35 shifting by members of the body other than the finger, specifically as shown in the drawing by the movement of the knee, although it is to be understood that the present invention is not so limited.

40 With these and other objects in view the invention comprises certain novel units, elements, parts, mechanical movements and combinations, as will be hereinafter more fully described and claimed.

45 In the drawings:

Figure 1 is a perspective view of one corner of a conventional typewriter supported upon a table with one embodiment of the invention applied thereto;

50 Figure 2 is a view in front elevation of the invention and a fragment of a typewriter;

Figure 3 is a view of the invention in edge elevation attached, and

55 Figure 4 is a perspective view of the clamping mechanism.

Like characters of reference indicate corresponding parts throughout the several views.

The exact type and design of the invention which forms the subject matter of this application will depend upon the proportion and relation of the several typewriter parts, as for instance the formation of the frame to which the device is attached and 60 the relation of the shift key to the frame, the device being mechanically varied to correspond, therefore, with different makes and models of machines. The disclosure in the drawing is not intended as disclosing 65 the invention except by way of illustration, and the invention is not limited to the precise mechanical features there disclosed. For the purpose of illustration, however, a typewriter has been conventionally shown at 70 10 supported upon a table 11. To the front frame part of the typewriter a clamp member, shown as an entirety at Figure 4, is applied. This clamp comprises a fulcrum member 12 and a keeper 13 hinged together 75 at 14 with a screw 15 inserted through perforations 16 for exerting tension between the keeper 13 and the fulcrum member 12, with a portion of the typewriter frame 10 therebetween, as indicated more particularly at Figure 3. As will be noted, the hinge 14 is below the bar of the frame 10 and the fulcrum member provides upstanding ears 17 for pivoting a rock bar 18. The rock bar is of such length and provided 80 with such extremity, of which the point 19 is an illustration, as to bear upon the shift key wherever located, as for instance, the key conventionally shown at 20, so that when the rock bar 18 is depressed from full line 85 position to dotted line position (Figure 3) the shift key 20 is depressed, thereby shifting the carriage shift in the usual well-known manner.

To actuate the rock bar 18 a lever 21 is 90 pivoted to the fulcrum member 12 at 22 and is provided with a cam extremity 23 bearing beneath a cam hook 24 on the rock bar 18. It will be apparent, therefore, that as the lever 21 is moved from full line position to 95 dotted line position (Figure 2) the action of the cam 23 on the cam 24 will be to depress the rock bar 18, as hereinbefore mentioned. The movement of the lever 21 in the particular type of device shown in the drawings is accomplished by providing a section 100

25 on the lever 21 to be engaged by the knee 105

110

of the operator for moving the lever as indicated, relying upon the spring actuation of the key 20 to return the parts to normal or full line position.

- 5 It will be apparent, therefore, that by oscillating the lever 21 upon its fulcrum 22 the rock bar 18 will be oscillated upon its pivot 17 to alternately depress the key 20 and permit its returning to normal. This oscillation will be accomplished by the particular type of device shown in the drawings by the knee, as stated, which leaves the hands and fingers of the operator free for actuating the printing keys as usual. In this 15 manner the speed of the operator is very greatly enhanced, while fatigue is relieved by making use of a greater number of members of the body for accomplishing the actuation of the mechanical parts.
- 20 While the term "carriage shift" has been employed in this specification, it is to be understood that the invention is not limited to the actual shifting of the carriage itself, but applicable as well to that type of machines wherein the shift key accomplishes the shifting of the battery of type bars, as well as to that type of machine where the shift key actually shifts the carriage or platen and includes any and all shifting 25 which accomplishes a change of capacity of the machine in writing classes of types of characters, as for instance, a shift from lower case letters to capitals, or any usual change within the practice of typewriting as now 30 understood or as may hereinafter be presented.

What I claim to be new is:

1. The combination with a typewriter embodying a shift key, of a rock bar fulcrumed 40 to the typewriter structure and bearing upon the key, a lever fulcrumed to the typewriter structure and depending below into position to be engaged by the knee of the operator and cam connection between the lever 45 and the rock bar, whereby the actuation of the lever is translated into rocking motion of the rock bar.
2. The combination with a typewriter em-

bodying a front rail and a shift key in the rear of the rail, of a rock bar pivoted to and 50 extending transversely across the rail and bearing upon the key, a lever fulcrumed to and swinging in a plane substantially parallel with the rail and perpendicular to the rock bar, and means to translate the movement of the lever into key-depressing movement of the rock bar.

3. The combination with a typewriter embodying a front rail and a shift key in the rear of the rail, of a rock bar pivoted to and 60 extending transversely across the rail and bearing upon the key, a lever fulcrumed to and swinging in a plane substantially parallel with the rail and perpendicular to the rock bar, and a cam carried by the lever to 65 translate the movement of the lever into key-depressing movement of the rock bar.

4. The combination with a typewriter embodying a front rail and a shift key in the rear of the rail, of a rock bar pivoted to and 70 extending transversely across the rail and bearing upon the key, a lever fulcrumed to and swinging in a plane substantially parallel with the rail and perpendicular to the rock bar, and a cam carried by the lever 75 bearing under the end of the rock bar opposite its engagement with the key to translate the movement of the lever into key-depressing movement of the rock bar.

5. The combination with a typewriter embodying a front rail and a shift key in the rear of the rail, a block clamped to the rail, a rock bar pivoted to the block and extending transversely above and across the rail 80 and bearing upon the key, a lever fulcrumed 85 to the front of the block and swinging in a plane substantially parallel with the rail and perpendicular to the rock bar, and means to translate the movement of the lever into key-depressing movement of the rock bar. 90

In testimony whereof I hereunto affix my signature in presence of two witnesses.

ROCKWELL A. LOOMIS.
